SPECIFICATION forming part of Design No. 34,713, dated July 2, 1901.

Application filed June 3, 1901. Serial No. 63,041. Term of patent 14 years.

To all whom it may concern:

Be it known that I, OSCAR H. GREENE, a citizen of the United States, residing at Redbluff, in the county of Tehama and State of California, have invented and produced a certain new and original Design for a Clothes-Pin; and I do declare the following to be a full, clear, and exact description of the invention, such as will enable others skilled in the art to which it appertains to make and use the same.

The invention relates to a new and original design for clothes-pins; and it consists of the design shown in the accompanying drawings, in which—

Figure 1 is a front elevation, and Fig. 2 is a side view.

The leading feature of the design consists of the vertical piece 1, terminating in the

jaws 2 and 3, diverging at their lower ends, 20 said jaws terminating in the coil 5, while the other upper end of the vertical piece terminates in a coil 6, the end of which in turn terminates in a downwardly and forwardly curved arm 7, having an eye 8 arranged immediately at the rear of the coil at the upper ends of the jaws.

What I claim is—

The design for a clothes-pin, as herein shown and described.

In testimony whereof I have hereunto set my hand in presence of two subscribing witnesses.

OSCAR H. GREENE.
